UNITED STATES PATENT OFFICE

155,158

DESIGN FOR A DOOR LOCK CASE

Carl A. Hillgren, Los Angeles, Calif.

Application September 16, 1947, Serial No. 141,424

Term of patent 7 years

(Cl. D50—5)

To all whom it may concern:

Be it known that I, Carl A. Hillgren, a citizen of the United States, residing at Los Angeles, in the county of Los Angeles, State of California, have invented a new, original, and ornamental Design for Door Lock Case, of which the following is a specification, reference being had to the accompanying drawings, forming a part thereof, in which:

Fig. 1 is a perspective view of a door lock case, showing my new design;

Fig. 2 is an elevational view thereof, taken from the indoor side of the case;

Fig. 3 is an outer end view thereof;

Fig. 4 is an elevational view, taken from the outdoor side of the case;

Fig. 5 is an inner end view thereof; and,

Fig. 6 is a top view of the case.

I claim:

The ornamental design for a door lock case, substantially as shown.

CARL A. HILLGREN.
